(57) **CLAIM**

The ornamental design for an abrasive sheet holder, as shown and described.

DESCRIPTION

3. Abrasive sheet holder

3.1 : Perspective

3.2 : Bottom

3.3 : Top

3.4 : Right

3.5 : Left

3.6 : Front

3.7 : Back

No(s) 3: Repro. No. 3.1 perspective oblique bottom view of a further alternative embodiment of an abrasive sheet holder showing our new design; Repro. No. 3.2 bottom plan view thereof; Repro. No. 3.3 top view thereof; Repro. No. 3.4 right side plan view thereof; Repro. No. 3.5 left side plan view thereof; Repro. No. 3.6 front plan view thereof; Repro. No. 3.7 back plan view thereof.

The portions shown in broken line form no part of the claimed design.
